UNITED STATES PATENT OFFICE.

ALBERT LUTHER VAN HOOZER, OF MARTINSVILLE, MISSOURI.

WIRELESS CHECK-ROW CORN-PLANTER.

SPECIFICATION forming part of Letters Patent No. 678,206, dated July 9, 1901.

Application filed December 31, 1900. Serial No. 41,737. (No model.)

To all whom it may concern:

Be it known that I, ALBERT LUTHER VAN HOOZER, a citizen of the United States, residing at Martinsville, in the county of Harrison and State of Missouri, have invented a new and useful Wireless Check-Row Device for Corn-Planters, of which the following is a specification.

This invention relates to check-row corn-
10 planters.

One of the principal objects of the present invention is to provide a device for checking ground which is operable independently of any check-line by devices carried on the machine in its progress across the field and which is so constructed as to form an attachment for ordinary seeders and planters, so that the checking device may be manufactured separately and readily applied to seeders and planters already in use, including those equipped with the ordinary check-row devices operable by means of a check-line stretched across the field.

In connection with the checking device hereinafter described I employ novel means for quickly setting the marker and seed-feeding devices, so that the driver may at any time adjust the marker and correspondingly adjust the seed-droppers, so as to properly line up the hills. The detailed objects and advantages of the invention will appear more fully in the course of the subjoined description.

The invention consists in a check-row planter attachment embodying certain novel features and details of construction and arrangement of parts, as hereinafter fully described, illustrated in the drawings, and incorporated in the claims.

40 In the accompanying drawings, Figure 1 is a plan view of a seeder and planter, showing the improved attachment applied thereto and in readiness for use. Fig. 2 is a vertical longitudinal section through the same. Fig. 3 is a vertical transverse section taken just in rear of the shaft on which the marker is mounted. Fig. 4 is an enlarged detail perspective view showing the trip-levers and the manner of mounting, limiting, and spring-
45 50 actuating the same.

Similar numerals of reference designate

corresponding parts in all the figures of the drawings.

The invention comprises, essentially, a marking rim or disk 1, which is mounted for rotation upon a shaft 2, journaled in bearings 3, 4, and 5, the bearings 3 and 5 being connected by the end portions of a pair of arms or brackets 6, bolted or otherwise secured at their opposite ends, as at 7, to the main cross-bar 8, arranged near the front of the machine and forming a permanent part of a seeder or planter of well-known type. The intermediate bearing 4 is carried by the upper end of the inclined post or brace 9, secured at its lower end to one of the legs, boots, or conducting-tubes 10 of the machine. The shaft 2 extends transversely of the machine or at right angles to the line of draft and parallel with the main axle 11 and is provided at its inner end with a setting-wheel 12, the periphery of which is notched or toothed, adapting it to be engaged by a latch 13, carried by a thumb-latch setting-lever 14 and normally held out of engagement with the wheel 12 by means of the spring 15 encircling the latch-operating rod or stem 16, which connects with the thumb-latch 17 at the free end of the lever, as clearly shown in Figs. 1 and 2.

80 The marking rim or disk is provided at intervals with markers 18, having pointed or sharpened outer edges 19 and longitudinally-slotted shanks 20, which receive one or more set-screws 21, which pass through the slots 20 into the rim or disk, thus providing for the adjustment of the markers in radial directions, so as to adapt the marking device to hard or soft soils, it being desirable to decrease the depth of penetration of the markers when operating in hard soil and increase their depth of penetration when operating in soft soil. The rim or disk 1 is further provided at like intervals with lateral projections 22 on its inner side, said projections constituting cams 95 for imparting motion to the seed-dropping devices hereinafter described. The cams 22 are so arranged with respect to each other and the markers that they are enabled to trip the seed-droppers at the same moment that the markers are indenting the soil.

85 90 95 The inner bracket or arm 7 is reduced in-

termidate its ends to form a fulcrum or fixed shaft 23, upon which the seed-dropping trip-lever 24 is mounted. The lever 24 is fulcrumed intermediate its ends on the shaft 23, 5 and its longer arm is provided at the extremity with a segmentally-shaped runner or cam 25, adapted to coöperate with the cams 22 successively as the marker rim or disk 1 revolves in contact with the ground. The 10 shorter arm 24' of the lever 24 extends below the fulcrum or shaft 23, where it is provided with a cross-head 26, the object of which will hereinafter appear. In order to limit and steady the rocking movements of the trip-lever 24, I provide a cage 27, comprising an upper rectangular frame 28 and downwardly-converging arms or legs 29, connected at their extremities to the fixed shaft or fulcrum 23, as clearly illustrated in Fig. 4. The lever is 15 also provided with an extension 30, substantially L-shaped and having one branch connected directly to the lever 24 proper, while the other branch is provided with a bearing 31, encircling the fulcrum or shaft 23. The 20 trip-lever 24 is normally held in the direction of the marker rim or disk by means of one or more springs 32, coiled around the shaft or fulcrum 23 and having one end connected to the shaft, while the opposite end is connected 25 to the lever 24 or the extension 30 thereof, said spring exerting its tension to hold the lever in the position in Fig. 4 and with the runner 25 held against the marker rim or disk. The cage 27, by reason of its shape, serves to 30 limit and steady the vibratory movements of the trip-lever in both directions. Extending laterally from the bracket 7 or from the fulcrum portion 23 thereof is a stop 33, which extends across the path of the heel extension 34 of the marker-setting lever 14, so that when 35 said lever 14 is released and dropped to its normal carrying position the said lever will rest in contact with the lower surface of the stop 33, thus preventing it from falling and 40 bearing against the rotating main axle 11 of the machine.

The machine is equipped with the usual runners or furrow-openers 35 and boots 36, and the boots are provided at suitable points 45 with gates 37 for arresting the supply of seed gravitating from the superimposed seed-boxes 38. Each of the gates 37 is mounted upon a rock-shaft 39, which is provided with a crank-arm 40, from one of which a link 41 50 extends to the cross-head 26, hereinabove described. The operating-link for one gate is attached to one end of the cross-head 26, while the operating-link 47 of the other gate is attached to the opposite end of the cross-head, as clearly shown in Fig. 3. The link 47 connects at its outer end with one arm of a bell-crank 48, the other arm of which is connected by a short link 49 with the crank 40 of the adjacent gate 37. The gates are so 55 mounted and arranged that when the trip-lever is in its outward position said gates are closed, thus shutting off the supply of seed.

When, however, the trip-lever is rocked inward by the action of the cams on the marker-disk, the cross-head 26, operating in connection with the connecting-links 41 and 47, serves to rock the gates into a position which will allow the seed supported thereby to drop through the boots and be deposited in their respective furrows. The spring 32, which 60 returns the trip-lever to its normal position, also operates to close the gates 37 and prevent the dropping of the seed at inopportune moments.

For the purpose of illustrating the present invention I have shown the same applied to an ordinary seed-planter, in which the ordinary seedboxes 38 are employed, in connection with which any suitable seed-feeding devices may be employed, operated by a seed-shaft 42, having a clutch 43 and foot-lever 44, by means of which the clutch may be shifted and the seed-shaft and seed-feeding devices thrown into or out of operation, the seed-shaft being shown as driven by 85 sprocket-gearing 45, connected with the main driving-shaft 11, on which are mounted carrying and covering wheels 46. Other parts of the machine not hereinabove particularly described may be constructed and arranged 90 in any usual or preferred manner.

From the foregoing description it will be seen that I have provided a very simple, cheap, and efficient marking and seed-dropping attachment for seeders and planters and 100 that the same may be readily applied to the common form of such machines in a very short space of time, thus doing away altogether with the check-line and operating devices incident to the use of such a line. The 105 marker performs its work as such simultaneously with the tripping of the gates which uphold the seed, so that the operator knows exactly where the hills are being made. The 110 lining up of the rows is greatly facilitated by means of the setting devices hereinabove described, the driver having merely to grasp the setting-lever 14, press the thumb-latch 17, thus throwing the latch into engagement with the setting-wheel 12, whereupon he may 115 turn the marker-rim to any desired degree until one of the markers registers with one of the marks made in the previous row. The operator then releases the thumb-latch and 120 the setting-lever until the same is caught and held by the limiting-stop 33 referred to.

From the foregoing it is thought that the construction, operation, and many advantages of the herein-described check-row corn-planter will be readily apparent to those 125 skilled in the art without further description, and it will be understood that various changes in the form, proportion, and minor details of construction may be resorted to without departing from the principle or sacrificing any 130 of the advantages of this invention.

Having thus described the invention, what is claimed as new, and desired to be secured by Letters Patent, is—

1. A rotary marker comprising a shaft, a marker-rim thereon, and a marker-setting lever journaled on said shaft and provided with means for coupling the lever to the said shaft and uncoupling the same therefrom.
- 5 2. A rotary marker comprising a shaft, a marker-rim fast thereon, a setting-wheel fixed on said shaft, and a setting-lever on said shaft and provided with means for connecting the lever with the setting-wheel and disconnecting it therefrom.
- 10 3. A rotary marker comprising a shaft, a marker-rim fast thereon, a setting-wheel fast on said shaft, and a thumb-latch lever provided with means adapted to engage directly with the setting-wheel, but normally disconnected therefrom.
- 15 4. The combination with a traction marker-rim and means for setting the same, a boot, and seed-dropping devices coacting with the boot, of cam projections fast on the rim at one side thereof, a trip-lever actuated by said projections and adapted to swing transversely of the machine, and operating connections between the lever and the lower seed-dropping devices.
- 20 5. The combination with a traction marker-rim, a boot, and seed-dropping devices coacting with the boot, of a trip-lever operatively associated with the rim and mounted to swing transversely of the machine-frame, a cross-head on said lever, and a plurality of operating connections interposed between said cross-head and the lower seed-dropping devices.
- 25 6. The combination with a traction marker-rim, a boot, and seed-dropping devices coacting with the boot, of a trip-lever actuated directly by the marker-rim, connections between said lever and the lower seed-dropping devices, and means in the path of said lever for limiting the vibratory movements thereof.
- 30 7. The combination with a traction marker-rim, a boot, and seed-dropping devices coacting with the boot, of a trip-lever actuated directly by the marker-rim, connections be-
- 35 tween one end of said lever and the lower seed-dropping devices, and means for yieldingly holding the opposite end of said lever in engagement with the marker-rim.
- 40 8. The combination with a traction marker-rim, a boot, and seed-dropping devices coacting with the boot, of a trip-lever actuated directly by the marker-rim, connections between one end of said lever and the lower seed-dropping devices, and a spring acting directly on said lever for holding the opposite end thereof in engagement with the marker-arm.
- 45 9. The combination with a traction marker-rim, and seed-dropping devices, of a trip-lever actuated by the marker-rim, connections between said lever and the seed-dropping devices, a lever extension, a stationary shaft upon which the lever and its extension are fulcrumed, and means associated with the lever and its extension for limiting the movements of the lever in opposite directions.
- 50 10. The combination with a traction marker-rim, and seed-dropping devices, of a trip-lever actuated by said rim, connections between the lever and the lower seed-dropping devices, a lateral extension on said lever, and a cage embracing the lever and its extension for limiting the movements of the lever in opposite directions.
- 55 11. The combination with a traction marker-rim, and seed-dropping devices, of cam projections on the rim, a trip-lever provided with a rim-engaging runner adapted to co-operate with said cam projections, and connections between the lever and the lower seed-dropping devices.
- 60 In testimony that I claim the foregoing as my own I have hereto affixed my signature in the presence of two witnesses.
- 65 ALBERT LUTHER VAN HOOZER.
